UNITED STATES PATENT OFFICE.

HUGO ACKERMANN, OF GODESBERG-ON-THE-RHINE, GERMANY.

PRESS FOR THE MANUFACTURE OF ARTIFICIAL STONES, BLOCKS, BRICKS, OR THE LIKE.

Application filed March 17, 1927, Serial No. 176,139, and in Germany March 17, 1926.

The invention relates to presses for the manufacture of artificial stones, blocks, bricks or the like, such as refractory bricks, for instance, and in particular to hydraulic presses with upper and lower pressing dies.

The object of the invention is to provide means whereby in presses, the press table of which is provided with a number of moulding openings wedge shaped bricks or bricks of any appropriate profile can be manufactured.

Another object of the invention is to provide means for filling simultaneously the mould openings by means of a charging box, without any loss of pressing mass filled in the compartments of the charging box.

Still another object of the invention is to provide means whereby the freshly pressed bricks despite their special cross-section can be removed from the press by mechanical means without damage.

The proper filling by means of a charging box is effected according to the invention by arranging on that part of the press table on which the charging box moves, that is, in front of the mould openings, ledges or rails the upper surface of which corresponds in shape to the upper surface of the lower dies. In the manufacture of wedge-shaped bricks the upper surface of the ledges or rails is slanting corresponding to the slanting upper surface of the lower dies. In the manufacture of profiled bricks the ledges or rails are profiled in accordance with the particular profile of the lower dies used at the time. The rear and front walls of the charging box are provided with recesses into which the slanting or profiled ledges or rails fit.

The proper removal of the pressed wedge-shaped or profiled bricks ejected from the mould openings and resting on the lower dies is effected according to the present invention by providing ledges or rails of corresponding shape on that side of the table on which the bricks are removed or in other words behind the mould openings.

The drawings illustrate the invention by a few applications which relate both to the manufacture of wedge-shaped as well as bricks of other profiles.

Fig. 1 shows a cross section through a press in which wedge-shaped bricks with two inclined surfaces are made.

Fig. 2 is a plan of the press shown in Fig. 1, whereby the upper press dies are omitted.

Fig. 3 is a section through the charging box in its position of rest along a line X/X in Fig. 2 on an enlarged scale.

Fig. 4 is, also on an enlarged scale, a section along a line Y/Y in Fig. 2 through that side of the press table on which the finished pressed bricks are shoved off.

Fig. 5 is a plan of a press table in which guiding ledges are only provided on the filling side, the finished pressed bricks being shoved off on the level surface of the table.

Figs. 6-12 show various kinds of profiled bricks and the profiled guide ledges to be arranged on the press table for this purpose in accordance with the invention.

Figures 1-4 apply to the arrangement of slanting table ledges as required for the manufacture of wedge-shaped bricks. The press table 1 is secured by the pillars 12 between the upper press cylinder 2 and the lower press cylinder 3. There are three mould openings 4 in the press table 1. The charging box 5 has in like manner three compartments. Each compartment of the charging box 5 is filled with pressing mass as required for one brick. A cross-beam 7 is fastened to the charging box by means of the bars 8, said cross beam, when the charging box is moved forward, driving the pressed bricks ejected from the mould openings along before it out of the range of the press dies.

Both the lower dies 9 and the upper dies 10 are provided with inclined heads in accordance with the slanting surfaces above and below of each wedge-shaped brick 8 to be made.

In Fig. 1 the press is shown at the moment in which, after finished pressing, the upper dies 10 have been withdrawn. The wedge-shaped bricks 8 are still in the position in which they have just been compressed on the press dies 9 and are about to be ejected from the mould openings by lifting the lower dies 9 and then carried away by the cross-beam 7.

The ledges or rails 11 provided with slanting surfaces are arranged on the press table 1 before and behind the mould openings 4. The slant of the surfaces of the ledges or

rails corresponds to the slant of the surfaces of the lower dies 9, so that the surface of each ledge 11 forms a plane with the surface of the corresponding lower die when 5 the latter on ejecting the wedge-shaped brick 8 is moved into its extreme upper position. Accordingly the wedge-shaped bricks 8, when the charging box is moved forward, can also be shoved along by the 10 cross-beam 7, on the slanting ledges 11 behind the mould openings on the side of removal without danger of disturbing the further pressing operations.

The front and rear walls of the charging 15 box 5 are provided below with recesses (Fig. 3) in which the slanting ledges or rails 11 fit. In moving forward the charging box 5 to the mould openings 4 the pressing mass glides along on the slanting ledges 20 11 without disturbance until it arrives over the adjoining slanting surfaces of the lower dies 9. The latter are now sunk down, whereby the pressing mass resting thereon follows, gliding out of the compartments of 25 the charging box into the mould openings beneath. This ensures a proper filling of the mould openings 4, whereby at the very beginning there is more pressing mass on the broader side of the wedge-shaped bricks 30 than on the narrow side. This distribution of the pressing mass in the mould opening ensures the production of wedge-shaped bricks which as a result of the exact distribution of the pressing mass throughout 35 their entire cross section are compressed with absolute uniformity.

The press shown in Fig. 5 is intended for the manufacture of profiled bricks shown in side and plan in Figs. 10 and 11. Three 40 mould openings 4 are provided in the press table 1 for simultaneously pressing three bricks. The charging box 5 glides on the side of the table in front of the mould openings. There are three guide ledges or rails 45 11^c fitted on this part of the table surface in front of the three mould openings 4. The arched ledges 11^c project through corresponding recesses in the walls of the charging box 5, serving as its bottom. The profile of the ledges 11^c will be seen at 16 in section in Fig. 10 and corresponds exactly to the surface profile to be used in this case, of the lower dies moved up and down in the 50 mould openings 4.

55 No guide ledges are provided in the example shown in Fig. 5 on that side of the press table on which the finished pressed bricks are shoved off by the cross-beam 7 into the position indicated by dotted lines, seeing 60 that the profiled brick shown in Figs. 10 and 11 possesses in itself a sufficiently large level resting surface, so that it can be shoved off directly over an even table surface.

65 Figs. 6 and 7 show in front and side view

a brick provided with groove 13 and tongue 14. In this case only narrow semicircular ledges 11^a, the cross-section of which corresponds to the groove, need be provided as guide ledges on the press table in front of 70 the mould openings.

The profiled brick shown in side view and plan in Figs. 8 and 9 illustrates still another application of the invention. This brick is cut out at the point 15 on the upper and lower side. In this case the guide ledges 11^b must correspond to the cutout on the lower side. The advantages of the present invention become particularly evident in considering the ridged brick shown in front view in Fig. 12 which on account of the ridges on its upper and lower surface presents to view a number of ribs 17 which require a ledge 11^d of corresponding profile on the press table 1.

80 The advantage gained by the arrangement of ledges with slanting or otherwise inclined profiled surface is that the pressing mass charge in the charging box has already assumed on its lower surface the profile of the brick to be pressed, is brought to the mould openings in this form and set unchanged on the lower dies. The shape of the pressing mass charge previously formed in this manner is also still retained when 85 the charge sinks into the mould openings by letting down the lower dies.

90 The profiled ledges arranged in accordance with the invention on the charging side of the press table ensure not only an acceleration 100 of the pressing operations by the charging box operating in connection with the ledges, but also a considerably improved compression and structure of the pressed 105 bricks due to the fact that the charge in the mould openings has been given before compression a similar shape to that of the pressed bricks. This further ensures a uniform 110 pressing effect on the entire pressing mass.

115 For this reason the new press table will also be used for making bricks which are only profiled on one surface and in cases where the brick can be pressed with the side not profiled turned downward. Even such 120 bricks can in future be pressed better with the profiled side turned downward, in order to ensure a uniform pressing effect by previously giving the pressing mass charge a form corresponding to the ultimate shape of the brick.

125 The ledges provided in accordance with the invention with slanting or profiled surface and arranged on the press table behind the mould openings ensure the removal of the pressed bricks without danger of injury. The pressed bricks carried off by the charging box or the cross-beam connected with same slide conveniently along on the profiled ledges adjoining with the surface of the 130

lower dies until they reach their places from which they are taken off. The pressed bricks accordingly retain their horizontal position without tilting during the course and, in 5 the event of their having recesses in their lower surfaces, are further supported by the profiled ledges corresponding to these recesses.

10 The shoving off of the pressed bricks from the press is, accordingly, effected on a press table built along the lines set forth in the invention, without alteration of shape and without injury to the bricks.

What I claim is:

15 1. A press for the manufacture of wedge shaped or otherwise profiled bricks, comprising upper and lower pressing dies, a press table provided with a plurality of moulding openings and an equal number of guide 20 ledges or rails, arranged before the mould openings and corresponding in shape to the upper surface of the lower pressing dies and a charging box having the front and rear wall formed with bottom edges corresponding 25 in shape to said ledges or rails.

2. A press for the manufacture of wedge shaped or otherwise profiled bricks, comprising upper and lower pressing dies, a press table provided with a plurality of moulding 30 openings and an equal number of guide 35 ledges or rails, arranged before and behind the mould openings and corresponding in shape to the upper surfaces of the lower pressing dies and a charging box, shiftable on said ledges or rails.

3. A press for the manufacture of wedge shaped or otherwise profiled bricks, comprising upper and lower pressing dies, a press table provided with a plurality of moulding 40 openings and an equal number of guide 45 ledges or rails corresponding in shape to the upper surface of the lower pressing dies and a charging box, shiftable on said ledges or rails and provided with a cross-beam for removing the pressed bricks from the mould openings.

In testimony whereof, I have signed my name to this specification at Cologne, Germany, this 26th day of February, 1927.

HUGO ACKERMANN.
